(57) **CLAIM**

The ornamental design for a low visual impact monopole tower for wireless communications, as shown and described.

DESCRIPTION

FIG. 1 is a front perspective view of the invention; FIG. 2 is a front elevational view of FIG. 1;

FIG. 3 is a right side elevational view of FIG. 1, the left side elevational view being a mirror image of the right side elevational view;

FIG. 4 is a rear elevational view of FIG. 1;

FIG. 5 is a top plan view of FIG. 1; and,

FIG. 6 is a bottom view of FIG. 1.

The elements shown in dash-dot lines form no part of the claimed invention, and are instead included to show environmental aspects of the claimed invention.
